UNITED STATES PATENT OFFICE

117,763

DESIGN FOR AN ELECTRIC FOOD MIXER

Hermann M. Alfred Strauss, Chicago, Ill., assignor to A. F. Dormeyer Mfg. Co., Chicago, Ill., a corporation of Illinois

Application September 2, 1938, Serial No. 79,684

Term of patent 14 years

To all whom it may concern:

Be it known that I, Hermann M. Alfred Strauss, a citizen of the German Republic, residing at Chicago, in the county of Cook and State of Illinois, have invented a new, original, and ornamental Design for Electric Food Mixers, of which the following is a specification, reference being had to the accompanying drawing, forming part thereof.

Fig. 1 is a side elevational view of an electric food mixer, embodying my new design;

Fig. 2 is a slightly reduced top plan view of the mixer;

Fig. 3 is a slightly reduced front elevational view of the mixer;

Fig. 4 is a slightly reduced rear elevational view of the mixer.

The dominant features of my design reside in the portions shown in solid lines.

I claim:

The ornamental design for an electric food mixer, as shown and described.

HERMANN M. ALFRED STRAUSS.
